(57) **CLAIM**

The ornamental design for a transport and stocking box, as shown and described.

DESCRIPTION

FIG. 1 is a front perspective view of the transport and stocking box in an open position shown with a removable flap; FIG. 2 is a front perspective view thereof shown in a closed position with the flap removed;

FIG. 3 is a top perspective view of FIG. 1; and, FIG. 4 is a right side elevational view of FIG. 2.

The broken lines are for the purpose of illustrating the environment of the design only and form no part of the claimed design.
